UNITED STATES PATENT OFFICE.

CARL E. LINDBERG, OF SILVERDALE, WASHINGTON.

HAND DRILL.

Application filed November 10, 1926. Serial No. 147,408.

My invention relates to drills and particularly to the type of small drill which is intended to be held in and operated by the hand.

5 The object of my invention is to provide a drill, particularly of this type, with means whereby it is provided with a store of inertia sufficient to enable it to overcome, without serious difficulty, relatively small 10 obstructions to its turning, such for instance as occur when a drill works through a thin sheet of metal.

My invention consists essentially in providing and mounting upon the drill a fly 15 wheel geared to the turning parts of the drill, so as to have a relatively high rate of rotation, whereby whenever the drill strikes anything which tends to stop it, the inertia of the rapidly revolving fly wheel will assist 20 the turning action of the hand to cause the bit to continue turning, thereby producing a more uniform and smooth action.

The particular parts and combinations of parts which I believe to be new, and upon 25 which I desire a patent, will be hereinafter particularly set forth in the claims.

In the accompanying drawings I have shown a construction in which my invention has been incorporated, the same being applied 30 to a small hand drill.

Figure 1 shows such a drill having my invention incorporated therein, with the major part of its mechanisms in section.

Figure 2 is a face view of the same drill. 35 In the drawings, 1 represents a frame which may be of any suitable construction, which provides the proper bearing and support for the various parts of the drill. This frame is provided with a handle 10 of ordinary construction, by which it may be held. It is also provided with a bit-carrying 40 shaft 11 journaled therein, and provided with any suitable means for holding the drill.

45 Secured upon and to turn with the bit-carrying shaft 11 are two gears 2 and 3. The gear 2 is a small gear and the gear 3 a much larger gear. These are bevel gears and mesh, respectively, with the gears 20 and 30, 50 which are, respectively, large and small gears, each meshing with its complemental gear as 2 and 3, that is, the small gear of each set meshes with the large gear of the other set.

55 The gears 20 and 30 are mounted to turn

about the same axis, this being represented by the shaft 40. They are, however, turnable independently of each other. The gear 30 has a fly wheel 4 secured thereto. A protective and enclosing casing 5 is provided 60 for this fly wheel, which casing also serves as the mount or carrier for the large gear 20 of the second set. The crank arm 6 and handle 60 by which the drill is operated, is 65 also secured to the casing 5.

The first set of gears consisting of the pinion 2 and gear 20 correspond with the two gears which are employed in the ordinary hand drill. The second set of gears consisting of the gear 3 and pinion 30 are 70 added gears which are employed in order to rotatively connect the fly wheel 4 with the bit-carrying shaft 11, and also for the purpose of securing a higher rate of rotation for the fly wheel. It is evident that the inertia of 75 the fly wheel depends to a very large extent upon its speed of rotation, and for this reason it is desirable to have it turn at a relatively much higher rate than does the bit-carrying shaft 11.

The method of mounting the fly wheel illustrated does not vary materially, change the size of the drill or make it cumbersome to handle or operate. It will be found that with such a fly wheel the drill may be used 85 to drill through such material as thin plates of metal without the objectionable effect usually found, due to the drill forcing its way through the sheet before it has entirely 90 cut away all of the material.

It is evident that many of the details of construction might be changed without in any essential way changing the principle of my invention. This principle does not include merely the mounting of a fly wheel 95 upon a drill, but the mounting of a fly wheel upon a drill in such a way as to make it adapted for application to hand drills of small size, and so as to protect the mechanisms essential thereto from injuring the 100 user.

What I claim as my invention is:

1. In a hand drill, in combination, a rotative bit-carrying shaft, a small and a large bevel gear fixed to said shaft, complemental 105 small and large gears independently turnable about the same axis and meshing each with its respective one of the first pair of gears, a fly wheel secured to the small gear of the second pair, a casing enclosing said fly wheel 110

and fixed to the larger gear of the second pair, and a turning crank fixed to said casing.

2. In a hand drill, a frame, a bit-carrying shaft journaled in said frame, a small and a large bevel gear secured to said shaft, a drum body having thereon a large bevel gear meshing with the smaller gear upon the bit-carrying shaft, said drum enclosing both

10 of the said gears, a transverse shaft carried by the frame and having the drum journaled thereon, a fly wheel journaled upon the same shaft and positioned within the drum and adjacent to its bottom, and a small gear secured to said fly wheel and meshing with the larger gear upon the bit-carrying shaft.

3. A drill comprising a frame, a bit-carrying shaft journaled in the frame, a large and a small gear secured to said shaft, a journal shaft mounted upon the frame at right angles to the bit-carrying shaft at one side only thereof, a small and a large gear independently journaled upon said

journal shaft and at the same side of the bit-carrying shaft, said latter gears meshing 25 each with its complementary one of the first pair, a fly wheel secured to the small gear of the second pair, a drum secured to the large gear of the second pair and enclosing the fly wheel and the second pair of gears, 30 and means for applying power to turn said drum and the connected gears.

4. The combination in a hand drill, of a bit-carrying member, a fly wheel geared to the bit-carrying member to turn at a higher rate than the bit-carrying member, an operating crank and gears rotatively connecting the crank with the bit-carrying member independently of the fly wheel connection therewith, and a protective casing for all of 40 said gears secured to and connecting the crank and the driving member of the bit-driving gears.

Signed at Silverdale, Kitsap County, Washington, this 3rd day of November, 1926.

CARL E. LINDBERG.
